DESIGN FOR A PIPE

George T. Ash, Washington, D. C.

Application September 24, 1945, Serial No. 122,273

Term of patent 14 years

(Cl. D85—8)

To all whom it may concern:

Be it known that I, George T. Ash, a citizen of the United States, residing at Washington, in the District of Columbia, have invented a new, original, and ornamental Design for Pipe, of which the following is a specification, reference being had to the accompanying drawing, forming part thereof.

Figure 1 is a side elevation of a pipe embodying the new and ornamental design.

Figure 2 is a bottom plan view thereof.

Figure 3 is a side elevation of the bowl and front portion of the stem of a pipe.

Figure 3a is a side elevation of rear portion of the stem thereof.

Figure 4 is a top plan view thereof.

The design resides in the contour and geometrical appearance of the pipe without reference to or restriction by the material of which the pipe is made or the coloration of the pipe.

What is claimed, is:

The ornamental design for a pipe, as shown.

GEORGE T. ASH.
